DESIGN FOR A CUP OR SIMILAR RECEPTACLE

Robert C. Fenner, Evanston, Ill., assignor to Vortex Cup Company, Chicago, Ill., a corporation of Delaware

Application August 14, 1933. Serial No. 49,028

Term of patent 7 years

To all whom it may concern:

Be it known that I, ROBERT C. FENNER, a citizen of the United States, and residing in the city of Evanston, in the county of Cook and State of Illinois, have invented a new, original, and ornamental Design for a Cup or Similar Receptacle, of which the following is the specification, reference being had to the accompanying drawing, forming a part thereof.

On the drawing:

Figure 2 is another side view of a cup taken from the handle side of the same.

Figure 3 is still a third side view of this cup looking at the cup from the opposite side from that on which the handle is disposed.

I claim:

The ornamental design for a cup or similar receptacle as shown.

ROBERT C. FENNER.
